UNITED STATES PATENT OFFICE.

WILLIAM SCOTT, OF MALDEN, MASSACHUSETTS.

CAR-COUPING.

SPECIFICATION forming part of Letters Patent No. 236,364, dated January 4, 1881.

Application filed March 19, 1880. (No model.)

To all whom it may concern:

Be it known that I, WILLIAM SCOTT, of Malden, in the county of Middlesex and State of Massachusetts, have invented certain new and useful Improvements in Couplings for Cars, of which the following is a specification.

This invention relates to improvements in car-couplings described in the specification accompanying my pending application for Letters Patent on car-couplings; and it consists more particularly in the construction of the shackling-pin and its arrangement and operation in combination with the shackling-link, all substantially as hereinafter described.

In the accompanying plate of drawings this improvement in couplings for cars is illustrated, Figure 1 being a side elevation of one of the couplers; Fig. 2, a vertical longitudinal section; Fig. 3, a longitudinal horizontal section on line $\alpha\alpha$, Fig. 1; and Fig. 4, a front view of Fig. 1, with the shackling-link in cross-section.

In the drawings, A represents one of my improved couplings for cars; B, a jaw arranged in a vertical position and projecting from the car at right angles to the end of the car, its upper end being shaped to make and form a buffer, C. The front end, a , of lower part b of the jaw B inclines downward, as shown at d , and on each side of said lower part is hung a shackling-link, D, for which a rest, e , is provided, suitably shaped and located to limit the upward and downward swing of the link D. So far the several parts as described are substantially the same as shown and described in the pending application before referred to, and the present improvements will now be fully described.

E is the shackling-pin. This pin is shaped as shown in the drawings, having an upright portion, f , and a toe portion, g , projecting substantially at a right angle therefrom toward and over the incline d of the lower part of jaw B. The upright portion f is square in cross-section, and is adapted to move freely up and down in a vertical socket, h , in the upper part of jaw B. The toe portion g and the lower end, l , of upright portion, which at such part is round in cross-section, rest in a correspondingly-shaped socket or recess, m , on the upper side of the lower part, b , of the jaw, which

socket serves as a seat for the shackling-pin, and also prevents any lateral play of the lower end of the pin and undue strain on its upright portion when the cars are coupled.

The coupling as above described is self-operating, and when two cars, each provided with one of these couplings, are brought together, end to end, the shackling-link of the car which then happens to lie the higher at its outer end slides up the shackling-link of the other car as the cars approach each other, and then up the incline d of the lower part of the jaw, and, passing under the toe portion g of the shackling-pin, between it and the incline, the pin is forced upward, and when the end of the shackling-link has passed beyond the pin, it (the pin) will then, by its own weight, drop through the loop of the link into its seat in the lower part of the jaw, when the cars will be coupled. To uncouple the cars, raise the pin, when the link can easily be removed. The pin can be provided with a cord or chain at its upper end for this purpose.

The back portion of the pin E can be inclined, as shown at n in the drawings, so that the pull of the link when the cars are coupled will tend to keep the pin in its seat, and thus prevent the accidental uncoupling of the cars. The toe end of the pin can have its under side shaped as shown in dotted lines in the drawings. Constructing the shackling-pin with a toe-projection so far forward insures the entrance of the link between it and the incline face of lower part of the jaw, and thus the easy and sure raising of the pin and consequent shackling of the cars.

Having thus described my invention, what I claim, and desire to secure by Letters Patent, is—

The draw-head A, constructed with the jaws B C, the latter projecting beyond the former to serve as a buffer, the link D, pivoted in and embracing the lower jaw, and the pin e, fixed on the lower jaw for limiting the movement of the link, in combination with the loose shackling-pin having the forward-projecting toe, all as herein shown and described.

WILLIAM SCOTT.
